APPARATUS FOR BEATING FIBROUS STOCK

William A. Kelley, Milwaukee, Wis.

Application January 2, 1937, Serial No. 118,743

8 Claims. (Cl. 92—22)

This invention relates to an apparatus for treating fibrous stock utilized for the manufacture of paper or similar material.

In the manufacture of paper the fibrous stock, prior to being fed to the paper making machine, is worked or treated in beaters, usually Hollander beaters, and in the Jordan refining engines.

While the invention will be described as applied to a Hollander type of beater, it is to be understood that it is applicable with equal advantage to other types of beaters such as the Thorsen Hery, Smith Egan, Vortex type beaters, or in fact any similar type of system of stock preparation wherein batches of stock are worked.

Up to the present time the extent to which the stock is worked in the beater has been left to the judgment of the beaterman who relies upon his experience and his observation of the condition of the stock to determine when the stock has been sufficiently worked. This practice has made it impossible to uniformly prepare the stock and as a consequence the stock, when manufactured into paper, varies in weight and in physical characteristics.

In Patent No. 1,883,051, granted October 18, 1932, to Oscar Stamets and Leon A. Duckworth for a control for motor driven apparatus, the electric motor which shifts the beater roll toward and away from the bed plate has its action controlled

or varied in accordance with the current in-put to the motor which rotates the beater roll. This method of control improves the beating operation since the current in-put to the beater roll driving motor depends upon the load, that is, the resistance to turning movement of the beater roll and further since the resistance to turning movement of the beater roll varies in accordance with the condition of the stock being worked. However, even with this improved method of control the extent to which the stock is worked or the time in which it is worked is still left to the judgment of the beaterman who is guided largely by the feel of the stock in his hand.

One of the objects of the invention is to insure uniform preparation of the stock. In carrying out this purpose, the first batch of the supply of stock worked in the beater is periodically sampled and laboratory tested until the stock is found to have the desired characteristics. For example, the stock may be subjected to freeness, mullen, tear, fold and tensile tests. The stock may be worked in a Hollander beater of the type wherein the position of the beater roll relative to the bed plate is controlled automatically in accordance with Patent No. 1,883,051. The gear-

ing between the electric motor and the lighter bars is also utilized to actuate an indexing or control mechanism having a dog whose position is varied in accordance with the position of the beater roll with respect to its bed plate. Associated with the indexing mechanism is a limit switch which, when operated, closes a circuit to a cycle timer. After the first batch of the stock has been properly worked in the beater the motor driving the beater roll is manually stopped and the dog is so set that when subsequent batches of the same supply of stock have been properly worked the dog will actuate or trip the limit switch and close the circuit to the cycle timer thereby stopping the beating by returning the beater roll to its starting position and, if desired, causing the operations following the beating to occur automatically and in proper sequence. For example, the cycle timer may be employed to stop the roll and raise it back to its starting position, ready for another cycle; open the dump valve to drop the stock into a stock chest; thereafter first open and then close the flush valves; then close the dump valve; next, first open and then close the valve which controls the supply of the next batch of stock to the beater, and finally throw the beater driving roll back under the control of the automatic device thereby starting another cycle.

Another object of the invention is to provide an apparatus of the character in question which is simple and durable in construction, reliable and efficient in operation, and easy and economical to manufacture, install and maintain.

Other objects and advantages reside in certain novel features of the construction, arrangement and combination of parts which will be herein-after more fully described and particularly pointed out in the appended claims, reference being had to the accompanying drawings forming a part of this specification, and in which:

Figure 1 is a plan view of a beater constructed in accordance with the present invention;

Figure 2 is a view thereon in side elevation, the beater being shown associated with a stock supply tank, the valves of which are illustrated diagrammatically;

Figure 3 is a fragmentary view partly in side elevation and partly in vertical section illustrating the indexing mechanism and the manner in which it is actuated;

Figure 4 is a view in elevation illustrating one type of cycle timer which may be employed;

Figure 5 is a view in section on line 5—5 of Figure 4;

Figure 6 is an elementary wiring diagram of the beater control circuits; and

Figure 7 is a graph illustrating the sequence and timing of the operations contemplated.

5 Referring to the drawings, the beater designated generally at B comprises a tank or trough 10. The usual central partition 11 is provided in the tank 10 and terminates short of the ends thereof. A suitable number of bed plates 12
 10 are provided. A beater roll 13 cooperates with the bed plates and is mounted on a shaft 14 with a pulley 15 whereby it may be driven from an electric motor (not shown). It is to be understood that the shaft 14 be driven in any
 15 suitable manner, that is, any type of gearing or motion transmission mechanism may be interposed between its driving electric motor and the shaft. The shaft 14 is rotatably mounted in bearings 16 provided on lighter bars 17 which
 20 are pivotally supported as at 18 in Figure 2 so that upon rocking of these bars upon their pivotal supports the beater roll 13 is shifted toward and away from the bed plates 12. The lighter bars 17 are constrained to corresponding
 25 rocking motion by means of a cross shaft 20 rotatably supported in bearings 21 and having crank arms 22 at its ends connected by means of links 23 to the lighter bars 17.

A small electric motor 25 is supported on one
 30 of the lighter bars and has its armature shaft coupled to or in driving connection with a speed reducer designated diagrammatically at 26. The speed reducer drives a pinion 27 which meshes with a large gear wheel 28 fixed to a horizontally
 35 disposed rotatable worm shaft 29. This shaft 29 has worms 30 secured thereto and meshing with worm wheels 31, the hubs of which are provided with threaded openings to engage the lighter bar screws 32. The screws 32 are anchored at their
 40 lower ends as indicated at 33 and their upper threaded portions pass through openings in the lighter bars. The worm nuts 31 bear against washers or suitable bearing surfaces 34 which surround the openings in the lighter bars through
 45 which the screws 32 extend.

When the motor 25 is run in one direction it will rotate the worm nuts 31 so as to depress the adjacent portions of the lighter bars thereby moving the beater roll away from its bed plates. Reversal of the motor 25 will move the beater roll toward the bed plates. The shaft 29 may also be provided with a hand wheel 29' whereby it may be manually turned.

The control for the motor which drives or
 55 rotates the beater and for the motor 25 is fully disclosed in Patent No. 1,883,051 and reference is made to said patent for a complete disclosure of these features.

The beater is equipped with a discharge opening 35 controlled by a dump valve designated diagrammatically at 36. The dump valve 36 is controlled as to its position by means of an electric motor 37 connected up to the dump valve by a suitable motion transmission mechanism designated diagrammatically at 38.

70 Valve controlled water supply devices or flush valves 40 and 41 overlie the beater tank and are employed for the usual purpose of flushing out the tank after each batch of stock has been worked. The valves 40 and 41 are of suitable construction, being preferably biased to closed position and opened electrically, that is, by an electromagnet, an electric motor, or the like.

The stock is supplied to the tank of the beater
 75 in any suitable way. For example, a suitable

conduit or pipe line may be led to the tank of the beater from any suitable source. The flow of the stock through the conduit may be controlled by a valve also motor operated if desired. In Figure 2, the stock is shown as being supplied to the tank of the beater from a stock supply tank 45 which receives its stock from a conduit 46 provided with a valve (motor operated) discharge fitting 47. The discharge opening of the tank 45 is also equipped with a motor operated discharge valve 48. The valves 47 and 48 are preferably controlled as to position by suitable electric motors.

The advantage of using a tank such as tank 45 is that it provides one convenient way of measuring the batches of the stock. It is desirable to have each batch of stock constituted of a certain definite amount. In the apparatus disclosed, for example, it would be practical to operate upon batches of stock weighing either 1000 pounds, 1500 pounds, or 2000 pounds.

The present invention proposes the provision on one of the lighter bars of an indexing or controlling mechanism designated generally at I. This indexing mechanism comprises a graduated disc 50 supported for rotation on a short shaft 51 mounted on the adjacent lighter bar. A dog 52 is carried by the periphery of the disc and is adjustable angularly thereabout. A suitable clamping member 53 is provided to releasably secure the dog in any adjustment. The shaft which carries the disc 50 is rotatably supported and also carries a gear wheel 54 which is the driven element of a reduction gear train 55 interposed between the shaft 51 and a driving pinion 56 fixed to and rotatable with the worm shaft 29.

With this construction the indexing disc 50 is rotated in one direction as the beater roll 13 moves towards its bed plates 12 and in the opposite direction as the beater roll moves away from its bed plates. And the extent of the motion in either direction depends upon the extent to which the beater roll is moved. Supported on the lighter bar which carries the motor 25 and in operative relation to the indexing mechanism I is a master limit switch 57 which has an operating element 58 lying in the path of movement of the dog 52 and adapted to be actuated thereby as the dog travels past the operating element.

The master limit switch is electrically connected to the circuit of a motor 60 of a cycle timer designated generally at C. This cycle timer may be mounted at any convenient point. The motor 60 drives a pinion 61 which meshes with a gear wheel 62 fixed to one end of a rotatable timer shaft 63. The shaft 63 is supported for rotation in bearings provided therefor in bracket plates 59 and carries a suitable number of cams designated at 64, 65, 66, 67, 68, 69 and 70. A panel of insulating material designated generally at 71 is also mounted on the bracket plates 64 and provides a support for electric switches 72, 73, 74, 75, 76, 77 and 78, and their binding posts which are designated at 80 in Figure 5. The switches 72 to 77 are of identical construction and each includes a fixed contact 81 carried by a supporting lug 82 secured to the panel 71, and a movable contact 83 engageable with the fixed contact and supported on a resilient arm 84. The end of the arm opposite the contact 83 is bowed as at 85 and fastened to the control panel. The inherent resilience of the arm 84 biases the contact 83 into engagement with the contact 81. Each arm 84 has a spring-like follower 86 which

is cooperatively related to the adjacent cam whereby when the high part of the cam comes around it will wipe against the follower and thereby flex the arm 84 to disengage its contact 5 83 from the cooperable contact 81 and consequently break the circuit controlled by these contacts.

In actual installations the beaters equipped with the Stamets-Duckworth control disclosed in 10 said Patent 1,883,051 have the current relay R of said patent, its pilot lamp P, rheostat R¹ for the load adjustment, a push button station for the push buttons B¹, B², B³ and B⁴ for raising and lowering and for either hand or automatic 15 operation, and the recording ammeter A for recording the power in-put into the main beater motor of said control, all mounted on a panel board. And in addition to the current transformer T¹, the reversing switch S and the potential transformer T of said patent, limit switches are provided, one of which is cut into the circuit to the side of the reversing switch which raises the roll and prevents the roll being raised too high by means of the hand switch, as 20 illustrated at 10' in Figure 6. A second limit switch designated at 11' (Figure 6) is also incorporated in the circuit connections of the other coil of the reversing switch.

Referring again to Figure 6, it will be seen 25 that when the dog 52 closes the master limit switch 57 coil 87 will be energized, the current flowing from power line 88 through wire 88', closed switch 75, wire 75', closed switch 57, wire 57', coil 87, wire 87' to the other power line 89. Coil 87, when energized, controls the position of 30 normally closed switches 90 and 91 and also of normally open switches 92, 93, 94 and 95. These switches 90, 91, 92, 93, 94 and 95 are interlocked as indicated diagrammatically in Figure 6, so that when the coil 87 is energized it opens the switches 90 and 91 and closes the switches 92, 93, 94 and 95.

When the switch 95 is closed it starts the cycle timer in operation inasmuch as current will flow 35 from power line 88 through wires 12' and 13', closed switch 95, wires 14' and 15', to the timer motor 60, and thence through wire 16' back to the other power line 89.

When the switch 90 is opened it cuts out the 40 automatic regulator of the Stamets-Duckworth control as will be obvious from Figure 6.

When the switch 92 is closed it energizes the coil corresponding to the coil 37 of the Stamets and Duckworth patent and consequently reverses the auxiliary motor 25 to cause it to raise the beater roll back to its starting position whereupon limit switch 10' is opened to stop the motor 25.

Closing of the switch 94 energizes the contactor 45 coil 96 which is effective to cause the motor 37 of the dump valve 36 to be operated to open the dump valve. When the dump valve 36 has been completely opened, limit switch 38' automatically stops the operation of the motor 37.

As the timer motor is now in operation its cams 50 will successively close switches 73 and 74 thereby successively energizing the coils 97 and 98. These coils 97 and 98 are in controlling relation to the flush valves 40 and 41 and when energized 55 open these valves whereas when de-energized allow the valves to close under the influence of their respective biasing means.

As will be understood from the diagram shown 60 in Figure 7, the switches 73 and 74 are closed for only a short time so that the flush valves are

automatically closed since opening of the switches 73 and 74 de-energizes their contactor coils 97 and 98.

In Figure 7 the arcuate lines in heavy black 5 graphically illustrate the time each of the switches 72 to 78, inclusive, are closed in each cycle and are numbered to correspond to their respective switches.

Further operation of the cycle timer causes one of its cams to open the switch 75. This 10 de-energizes the coil 87 and consequently results in the return of the switch 91 to its normally closed position thereby energizing the contactor coil 99 which is effective to reverse the operation of the motor 37 to cause it to close the dump 15 valve 36.

Continued operation of the timer causes the switch 76 to be closed thereby energizing the contactor coil 100 which controls the operation of the motor operated valve 48 and causes said 20 valve to be open until the operation of the motor is stopped by the action of limit switch 39'. As the timer shaft continues to rotate the switch 76 is opened and following that the switch 77 is closed thereby energizing the contactor coil 101 25 which reversely operates the motor valve 48 and causes this valve to be closed. Upon complete closing of the valve, limit switch 40' interrupts the operation of the motor which actuates the valve 48. 30

The switch 77 is next opened and shortly thereafter the continued rotation of the timer closes the switch 1 so as to again cut in the automatic regulator and the beating operation goes on. The timer continues to run until it 35 opens the switch 78 which cuts off the supply of current to the timer motor 60, the switch 95 also being opened at this time.

It will be understood from Figure 7 that the switch 78 is closed shortly after the timer begins 40 its operation so that current is supplied to the timer motor 60 even after the switch 95 returns to its normally open position upon de-energization of the coil 87. After the cycle of operation described the beating goes on until the dog 55 45 again closes the switch 57 whereupon the operations enumerated above are repeated.

In the operation of the device the adjusting rheostat of the Stamets-Duckworth control, which is connected across the coil of the current 50 relay, provides the means of adjusting the apparatus to maintain the desired load on the main motor. In beating the first batch of stock the main motor is set into operation and the beater roll is lowered by hand, that is, by utilizing the hand wheel H provided on one end of the shaft 55 29 or by closing the switches corresponding to switches B² and B³ of the control system of Patent No. 1,883,051, until the recording ammeter indicates the desired load on the main motor. The switch corresponding to the switch B¹ of 60 Patent No. 1,883,051 is now closed so that the beater is thrown over to automatic operation and at this time the rheostat is adjusted until the balanced lever of the current relay of the 65 Stamets-Duckworth control is in a balanced position. This will maintain a constant load on the motor as pointed out in Patent No. 1,883,051. If the load is greater than the predetermined amount the current relay will close one contact 70 and through the reversing switch will turn the control motor in the direction to raise the roll off from the bed plate. Likewise, if the load becomes less than the desired amount the current relay will close the other circuit which will 75

lower the roll on the bed plate, thus increasing the load on the main motor.

As the operation continues the fibrous stock is periodically sampled and laboratory tested until it has been worked to the desired extent and possesses the desirable characteristics. The beating operation is then manually stopped and the dog 52 is adjusted so that in beating subsequent batches of stock, when the roll occupies the position corresponding to its final position in beating the first batch, the dog 52 will automatically trip the limit switch 57.

It is to be understood that the fundamental feature of novelty of the present invention resides in the discovery that there is a definite relationship between characteristics of the stock and beater roll position with respect to the bed plate when the power input to the roll is maintained substantially constant and the beating cycle is allowed to vary through a longer or a shorter period according to the consistency and/or hardness of the stock. This discovery is utilized in the present invention by first, periodically testing and sampling the first batch of stock until it has been properly prepared. Second, during the working of the first batch of stock indexing or measuring the motion of the beater roll or similar element toward the bed plate or cooperable element. Third, utilizing the measurement or indexing in a mechanical or electrical way to terminate the working of subsequent batches of the stock. This last operation is usually accomplished by causing the auxiliary motor to return the beater roll back to its starting position when the stock has been properly prepared or worked. In addition to the foregoing, the invention also contemplates combining with this fundamental combination the cycle timer and auxiliary apparatus hereinabove described.

It is important to note that it is the final roll position which determines the time at which the working or preparation of the stock is terminated, irrespective of the initial or starting position of the roll. The initial or starting position of the roll is determined automatically by the consistency and/or hardness of the stock and the automatic control means which maintains substantially constant power input to the beater roll. As a consequence, even though batches vary somewhat in hardness or in similar properties and a somewhat longer time may be required for their proper preparation or working the operation will be carried on to its completion since it is the final roll position rather than time that is the controlling factor. And furthermore, the cessation of the working or preparation is entirely independent of the starting or original position of the roll.

While I have shown and described one apparatus and one method embodying the present invention, it is to be understood that the particulars of this disclosure are to be considered as illustrative rather than restrictive and that various changes within the spirit of the invention and the scope of the subjoined claims are contemplated.

The invention claimed is:

1. An apparatus for beating fibrous stock comprising a trough, a bed plate therein, a beater roll cooperable with the bed plate, a main electric motor for rotating said beater roll, lighter bars carrying said roll, gearing for swinging said lighter bars to shift said roll toward and away from said bed plate, an auxiliary electric motor

for actuating said gearing, means for causing the auxiliary motor to lower the lighter bars when the current input to the main motor decreases below a predetermined value and to raise the lighter bars when the current input to the main motor increases above said value, a master control device operable when actuated to shut off the supply of current to said main motor, indexing mechanism driven by said bearing and including means to register the position of the beater roll relative to the bed plate, and settable means cooperable with said registering means and also cooperable with the master control device whereby the beating cycle may be terminated in response to movement of the beater roll to a predetermined position.

2. An apparatus for beating fibrous stock comprising a trough, a bed plate therein, a beater roll cooperable with the bed plate, a main electric motor for rotating said beater roll, lighter bars carrying said roll, gearing for swinging said lighter bars to shift said roll toward and away from said bed plate, an auxiliary electric motor for actuating said gearing, means for causing the auxiliary motor to lower the lighter bars when the current input to the main motor decreases below a predetermined value and to raise the lighter bars when the current input to the main motor increases above said value, a master control device operable when actuated to shut off the supply of current to said main motor, indexing mechanism driven by said gearing and including a disk rotated to an extent proportional to the advance of the beater roll toward the bed plate and having means thereon to indicate the position of the beater roll with respect to the bed plate, and a dog adjustably interconnected with the disk and cooperable with the master control device for tripping the same whereby the beating cycle may be terminated in response to movement of the beater roll to a predetermined position.

3. An apparatus for beating fibrous stock comprising a trough, a bed plate therein, a beater roll cooperable with the bed plate, a main electric motor for rotating said beater roll, lighter bars carrying said roll, gearing for swinging said lighter bars to shift said roll toward and away from said bed plate, an auxiliary electric motor for actuating said gearing, means for causing the auxiliary motor to lower the lighter bars when the current input to the main motor decreases below a predetermined value and to raise the lighter bars when the current input to the main motor increases above said value, a master control device operable when actuated to shut off the supply of current to said main motor, indexing mechanism driven by said gearing, motor actuated instrumentalities associated with the trough for performing operations corelated to the beating of the fibrous stock, a cycle timer operable to control the action of said motors and said motor actuated instrumentalities, and means actuated by said indexing mechanism to control the operation of said cycle timer.

4. An apparatus for beating fibrous stock comprising a trough, a bed plate therein, a beater roll cooperable with the bed plate, a main electric motor for rotating said beater roll, lighter bars carrying said roll, gearing for swinging said lighter bars to shift said roll toward and away from said bed plate, an auxiliary electric motor for actuating said gearing, means for causing the auxiliary motor to lower the lighter bars when

the current input to the main motor decreases below a predetermined value and to raise the lighter bars when the current input to the main motor increases above said value, a master control device operable when actuated to shut off the supply of current to said main motor, indexing mechanism driven by said gearing, a motor operable dump valve for said trough, a motor operated flushing device overlying said trough, a motor operated stock supply connection leading to said trough, a cycle timer in controlling relation to all of said motors, and means actuated by said indexing mechanism for setting said cycle timer into operation.

5. In a beater including a bed plate, a rotatable beater roll, means for supporting the roll for movement towards and from the bed plate, a motor for driving the roll, electric control means for maintaining substantially constant predetermined load on said motor, said control means including means for moving the roll away from the bed plate as the load on the motor tends to rise above said predetermined load and for moving the roll towards the bed plate as the load on the motor tends to fall below said predetermined load, the combination with said roll moving means of means movable thereby and concurrently with the beater roll for indicating the position of the roll with respect to the bed plate, switch means operable, when actuated, to terminate the beating cycle, and means carried by the indicator and movable therewith to engage the said switch means and actuate the same when the beater roll is moved to a predetermined position with respect to the bed plate.

6. In a beater, a bed plate, a rotatable beater roll, means for supporting the roll for movement towards and away from the bed plate, a motor for driving the roll, control means for maintaining substantially constant predetermined load on said motor, said control means including means for moving the roll away from the bed plate as the load on the motor tends to rise above said predetermined load, and means for moving the roll toward the bed plate as the load on the motor tends to fall below said predetermined load, master control means operable when actuated to deenergize the first mentioned control means and to deenergize the roll driving motor, and means

operatively connected with said roll moving means for actuating said master control means when the roll reaches a predetermined position with respect to the bed plate to thereby terminate the beating cycle.

7. In a beater, a bed plate, a rotatable beater roll, means for supporting the roll for movement towards and from the bed plate, means for driving the roll, control means for maintaining substantially constant resistance to turning movement of the roll, said control means including means for moving the roll away from the bed plate as the resistance to turning movement of the roll tends to rise above said predetermined resistance, and for moving the roll towards the bed plate as the resistance to turning movement tends to fall below said predetermined resistance to turning, means for automatically terminating the beating cycle when the roll reaches a predetermined position in respect to the bed plate, 20 said last-mentioned means including a member movable by the roll moving means to positions corresponding to the positions of the beater roll with respect to the bed plate, and stop means, operable by said movable member when the beating roll reaches a predetermined position in respect to the bed plate.

8. In a beater, a bed plate, a rotatable beater roll, means for supporting the roll for movement towards and away from the bed plate, a motor for driving the roll, control means for maintaining substantially constant predetermined load on said motor, said control means including means for moving the roll away from the bed plate as the load on the motor tends to rise above said predetermined load, and means for moving the roll toward the bed plate as the load on the motor tends to fall below said predetermined load, master control means effective when actuated to deenergize the first mentioned control means and to energize the roll moving means to raise the roll away from the bed plate, and means operatively connected to said roll moving means to actuate said master control means upon movement of the roll to a predetermined position in respect to the bed plate to thereby terminate the beating cycle.

WILLIAM A. KELLEY.
